UNITED STATES PATENT OFFICE.

WALTER WERNER, OF HOOSICK FALLS, NEW YORK, ASSIGNOR TO THE NOBLE & WOOD MACHINE CO., OF HOOSICK FALLS, NEW YORK, A CORPORATION OF NEW YORK.

EXTRACTOR FOR PULPING DEVICES.

Application filed August 29, 1928. Serial No. 302,679.

This invention relates to pulping devices in general, and particularly to those provided with means for extracting fined stock therefrom.

5 The object of this invention is to provide an improved method and means for automatically extracting the sufficiently fined stock from pulping engines, tub beaters, and other devices wherein the hydrated stock is 10 caused to circulate under the urge of propelling mechanism.

The manner in which I have accomplished my object is illustrated by the accompanying drawings, which are in a certain sense illustrative only, and in which:

15 Fig. 1 is a plan view of a tub beater (parts broken away) provided with my improved continuous extractor; and Fig. 2 an irregular section as along the line 2—2 on Fig. 1, propeller and shaft not being cut.

20 Fig. 3 is a fragmentary section through the extractor point in a tub beater provided with my improved extractor, and illustrates a modified form of extracting port.

25 The same reference characters refer to the same parts throughout the several views.

Referring to the drawings, "A" represents the tub embodying this invention; "B" and "C" the usual beater roll and bed plate; and 30 "D" the back fall. "M" represents the mid-feather which in the form illustrated divides at the one end so as to form the diverging walls "F" and "G" which extend across and block the usual free way between the mid-feather and the wall of the tub.

35 Each of the walls "F" and "G" has an opening therethrough, the two being in alignment, and in these openings a perforated tubular shell "H" is secured in any suitable manner. 40 This tubular shell spans the space between the walls "F" and "G" and so forms a covered passageway which interrupts the usual channel-way for the passage of the work, and into which the whole of the work must enter 45 when being circulated under the impulsion of the beater roll "B".

The shell "H" preferably has a natural capacity somewhat less than would be required to permit the ordinary free flow of the work therethrough without increasing its rate of travel, and when the beater is running normal the entrance to this shell or passageway is to be completely submerged.

50 Mounted in the shell "H" which forms the wall of the covered passageway (in this case

from one side of the tub to the other) and at or near the end thereof where the work will normally enter, is a propeller "K", which is secured on a shaft mounted concentric with the shell "H", and adapted to be driven from 60 an available source of power in any suitable manner. No details of the shaft mounting or the manner in which it may be driven is shown.

While I have illustrated my improved extractor as being installed at the end of the tub just behind the back fall, I may locate it at the opposite end, or at some point in its length; and while I have illustrated it only as applied to a tub beater, it may be applied 70 to other forms of pulping devices as well.

My improved continuous extractor operates as follows:

When a pulping device equipped therewith is operating normally, i. e. with a normal 75 amount of hydrated stock and at the normal speed, the stock is driven along under the urge of the propelling mechanism (in the installation illustrated this is a beater roll) against the wall "G" and/or into the entrance 80 end of the covered passageway formed by the perforated shell "H". It here comes into contact with the propeller "K" which is adapted not only to speed up its rate of travel but to also urge it toward and against 85 the perforations in the wall of the passageway over which it will flow, and through which the sufficiently fined parts of the stock will escape and so leave the tub by way of the exit port "E".

90 By causing the work to flow through the covered passageway at a comparatively high speed I find that there is little, if any tendency for the perforations to become clogged; the force of the flowing stock being sufficient 95 to keep the perforations clear.

I claim:

1. In a pulping device: an extractor comprising a tubular member with perforations through the wall thereof, said member located and so mounted in the channel-way for the stock that all of it must pass thereinto as it is circulated; and means whereby stock escaping from said tubular member through said perforations will be conducted out of 100 the device.

105 2. In a pulping device: an extractor comprising a tubular member with perforations through the wall thereof, said member located and so mounted in the channel-way for 110

the stock being worked that said stock must pass thereinto when it is circulated; means for speeding up the rate of travel of and forcing said stock toward and against the 5 wall of said tubular member as it travels therethrough; and means whereby stock escaping from said tubular member through said perforations will be conducted out of the device.

10 3. In a tub beater: a covered passageway interrupting and somewhat restricting the channel way between the mid-feather and the wall of the tub; perforations through the wall of said passageway; an exit port where- 15 by matter escaping from said passageway through said perforations will be delivered outside the tub; and means for speeding up the flow of stock through said passageway sufficiently to nullify the blocking effect 20 thereof upon the circulation.

4. In a usual tub beater: a spaced pair of partition walls blocking the normal channel-way between the mid-feather and the wall of the tub; a perforated tubular member mounted in and through said spaced pair of partition walls and bridging the space therebetween; and an exit port from between said partitions to the outside of the tub. 25

5. In a pulping engine: a normally submerged tubular member forming a part of 30 the channel-way for the stock being worked; perforations through the wall of said passageway; means for directing the stock passing through said tubular member toward said perforations; and means whereby matter es- 35 caping through said perforations will be delivered outside the engine.

In testimony whereof I have affixed my signature.

WALTER WERNER.
